UNITED STATES PATENT OFFICE.

BRONISLAW GWODZ, OF WARSAW, POLAND.

TAKE-UP SPROCKET FOR MOTION-PICTURE MACHINES.

Application filed August 26, 1921. Serial No. 495,702.

To all whom it may concern:

Be it known that I, BRONISLAW Gwozdz, a citizen of the Polish Republic, residing at Warsaw, Poland, have invented certain new and useful Improvements in Take-Up Sprockets for Motion-Picture Machines (for which I have filed application in Germany August 2, 1920, patent not yet granted), of which the following is a specification.

10 My invention relates to kinematographs and more especially to driving rollers for motion picture films. It is well known that the celluloid film strips employed in kinematographic apparatus are driven by toothed rollers, the teeth of which engage perforations along the edges of the film strip. It is also known that this manner of driving the picture strips wears the strip out very quickly, especially as in consequence of the extremely frequent change of pictures the strip is continuously stopped and started again. It is a matter of experience that the portions of the strip between the perforations suffer most and are first destroyed by the teeth of the driving rollers, so that a film which is otherwise quite intact becomes prematurely useless.

It has now been ascertained that this serious drawback is partly caused by the fact that the perforations in the strips show certain, although small irregularities and that above all the relation of the film to the driving device is during motion subject to certain irregularities, be it that the film is not properly introduced into the apparatus, be it that in the film itself tensions are set up during manufacture which cause the film to take a somewhat oblique course when passing over the rollers. It will be obvious that if rigidly connected toothed rims on the conveying roller act upon films having such irregularities fine cracks will soon form in the film, especially around the edges of the perforations, which cause a tearing of the strip, especially from perforation to perforation. As irregularities in the film strip cannot be avoided, it is an object of my invention to so construct the driving rollers and accessories that they can adapt themselves to these irregularities. This can be effected by making the toothed rims or discs of the driving rollers to a certain extent independent of one another, although they still cooperate in driving the strip. According to my invention, this is effected by adapting the toothed rims or discs to rotate relatively to one an-

other, by connecting them through a differential gearing or the like. They are then capable of rotating relatively to one another and will yet turn round with the roller. A 60 full description of the invention will be found in the following specification.

I am aware that it is known to drive film-strips by means of two separate toothed discs which are permanently or only temporarily directly coupled by an external 65 gearing or a pawl.

In the drawings affixed to this specification and forming part thereof, my invention is illustrated by way of example. In the 70 drawings

Fig. 1 is a sectional elevation,

Fig. 2 is an end elevation,

Fig. 3 a section along line *c—d* and

Fig. 4 a section along line *a—b* in Fig. 1. 75

Referring to Fig. 1, 1 is the shaft of the driving roller, and 2 and 3 the two toothed discs which with their teeth engage the row of perforations along each edge of the film strip and thus cause the film to be carried so along.

Upon the shaft 1 there is fixed a sleeve 14, which in the middle between the discs 2 and 3 is provided with an annular collar 15. The hubs 8, 9 of the toothed discs are likewise provided with annular collars. These parts are connected by arms 16, which extend in the direction of the axis of the roller and are provided at their ends with rounded heads and in the middle with a rounded collar, as will be clearly seen particularly in Fig. 1. The middle portion rests loosely in the recesses 15' of the rings 15, while the rounded heads loosely engage appropriate recesses in the collars of the hubs 8 and 9 of the toothed discs 2 and 3. The rounded portions of the arms 16 permit a certain twist of the toothed discs 2 and 3 relatively to one another which amply suffices to compensate the irregularities in the film or in its guidance, as stated in the introduction to this specification. Here also the shaft 1 is provided with a disc 12 in the dished portion of which (curved to approximately a semi-circle) helical springs 13 are located (Fig. 3), which abut at one end against a radial projection 17 of the disc 12 and at the other end against a projection 18 of the toothed disc 2 and which operate as before described. 100

As a matter of course, the number of arms is not confined to the number shown in the 110

drawings, but may vary within wide limits. It will also be obvious that other modifications in the construction or arrangement of parts may be made without departing from the spirit of the invention, the principle of which has been set out in the introduction to the specification and some of the embodiments of which have been illustrated by way of example only.

10 I claim—

In a device of the kind described in combi-

nation, a shaft, a pair of toothed discs loose and a collar fixed on said shaft intermediate said discs, and flat arms extending through slots in said collar and engaging said discs 15 with their free ends, the contact surfaces of said arms with said collar and discs being rounded.

In testimony whereof I affix my signature.

BRONISLAW GWOZDZ.
